Assistant Examiner — Royner Mendoza

(74) Attorney, Agent, or Firm — Epstein Drangel LLP;
Robert L. Epstein(57) **CLAIM**

The ornamental design for an aerosol actuator, as shown and described.

DESCRIPTION

FIG. 1 is a front, top and right-side perspective view of an aerosol actuator showing our new design as it would appear mounted on an aerosol can;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a bottom plan view thereof; and,

FIG. 7 is a top plan view thereof.

The broken lines depict portions of the aerosol actuator that form no part of the claimed design.

The portions of the figures shown in broken lines are included to show the environment in which the aerosol actuator is intended to be used and do not constitute part of the claimed invention.

1 Claim, 6 Drawing Sheets(56)
